(57) **CLAIM**

We claim the ornamental design for a cat toy, as shown.

DESCRIPTION

FIG. 1 is a perspective view of the cat toy.

FIG. 2 is a top view thereof.

FIG. 3 is an exploded right side view thereof.

FIG. 4 is a left side view thereof.

FIG. 5 is a front view thereof.

FIG. 6 is a back view thereof; and,

FIG. 7 is a bottom view thereof.

The features shown in broken lines are for illustration only and depict portions of the cat toy that form no part of the claimed design.
